UNITED STATES PATENT OFFICE.

FRANK C. WHITE, MERIDEN, CONNECTICUT, ASSIGNOR, BY MESNE ASSIGNMENTS, TO SIMPLEX PLAYER ACTION COMPANY, INCORPORATED, OF NEW YORK, N. Y., A CORPORATION OF NEW YORK.

PLAYER PIANO.

Application filed March 24, 1921. Serial No. 455,346.

This invention relates to player pianos and more particularly to such instruments of the grand piano type.

It is a primary object of the invention 5 to provide an improved grand player piano having a simple, efficient and durable structural combination of pneumatically actuated and controlled mechanisms.

It is a further object to provide an improved player piano of the character mentioned, wherein the pneumatically actuated and controlled mechanisms are cooperatively associated in an assembled unit having a simple and permanently efficient connection 15 with the pneumatic power source.

It is a further object to provide an improved grand player piano wherein the said spool drawer carries in relatively fixed relationship the series of striker pneumatics 20 and wherein practical, improved operative connection is cooperatively disposed between the said striker pneumatics and the piano keys, permitting uniform play of the instrument in any relative adjustment of the 25 spool drawer with respect to the key bed.

It is, moreover, a general object of the invention to provide an improved grand player piano wherein the pneumatically actuated and controlled mechanisms possess features 30 of structural superiority and functional advantage.

Other objects and advantages will be in part noted hereinafter in connection with the following description of the accompanying 35 drawings, which illustrate an exemplary embodiment of the invention and wherein.

Figure 1 represents a side view of the improved grand player piano with certain parts broken away to show the disposition 40 of the spool and drawer and mechanisms associated in relatively fixed relationship therewith the drawer being shown as pushed in.

Figure 2 is a sectional view in the direction of the arrows on line 2—2, Fig. 1 with, also, certain parts broken away for better disclosure of the connections between the striker pneumatics and the piano parts actuated thereby;

Figure 3 is a top view of the spool drawer and mechanisms associated in relatively fixed relationship therewith;

Figure 4 is a fragmentary view corresponding in general to the front end of the

instrument shown in Figure 1, with the spool 55 drawer and associated mechanisms drawn outwardly, that is, as occupied during insertion or removal of the music rolls and, if desired, during manual expression control, as distinguished from automatic expression 60 control;

Figures 5 and 6 are fragmentary detailed views, on an enlarged scale, of a connection between a pneumatic action and part of the piano action cooperable therewith. 65

Figure 7 is a fragmentary side view of an improved connection between the pneumatic power source and the player action parts; and

Figure 8 is a vertical sectional view of Fig. 7, showing the telescopic joint of this connection. 70

Figure 9 is a plan view of what I term a coupler.

It has heretofore been a common practice 75 in grand player pianos to provide a drawer slidably supported below the key bed to receive the music roll and carry the tracker bar. In such pianos, however, it has been the further common practice to support the 80 striker pneumatics of the pneumatic action in fixed relationship to the main body of the piano and therefore in relatively movable relationship to the spool drawer. In such cases the action pneumatics and expression control mechanisms have been operatively connected with the tracker bar apertures and manual control devices, also on the spool drawer, by a large number of small 85 flexible rubber tubes disposed in different arrangements but of a length to extend from their connections on parts carried by the spool drawer, to other connections on parts carried by the piano body when the spool drawer is moved to its front limit. With 90 such constructions said small flexible rubber tubes, which have been of great number as from 80 to 120, have been subject to cracking and splitting and other objections in service. As above mentioned, it is one main object 95 of the present invention largely to eliminate said small flexible tubes heretofore employed, and provide an instrument capable of more permanent and satisfactory use.

As shown in Figure 1, the main case of the piano has a key bed 1 at the fore end, above which are arranged the usual piano keys 2, connected for manual actuation, in

any one of a variety of well understood ways, to the hammer action parts of the piano. Below the key bed there is provided by the present invention a drawer 3, slidably supported on guides 4 (Fig. 2) and capable of inward positioning (Fig. 1) such as occupied by the parts during manual play of the piano or, if preferred, during wholly automatic operation, and forward positioning (Fig. 4) to permit new music rolls to be inserted, and also to give access to the manual expression controls whenever the player wishes to control the expression by hand. At the rear of the drawer 3 the bank of striker pneumatics 7 are directly affixed, and, also to the drawer, are affixed the expression mechanisms 8 in such a manner that the drawer with the pneumatic action and expression mechanisms constitutes a distinct separable player unit.

It will be understood that the drawer 3 also contains the air motor for driving the music sheet, the automatic re-roll and repeat pneumatics, the manually controlled expression buttons, the automatic music roll tracking device and other necessary or desirable pneumatically controlled mechanisms. The note openings in the tracker bar are connected by ducts 9, which may be of rubber tubing or of metal, with the respective valve chests for the striker pneumatics 7 and the expression openings in the tracker bar are similarly connected by rubber or metal ducts 10 with chambers of the expression mechanisms 8. All of the pneumatically controlled mechanisms associated with the drawer 3, as mentioned above, are connected preferably by a single conduit 11 in communication with the main exhaust bellows 12 secured at the rear bottom of the piano and preferably driven by an electric motor 13. The conduit 11, (see Fig. 3) as shown, connects with branches 14 and 15 at the rear of the drawer which exhaust from the expression chambers 8 and are further connected to exhaust from the action chest and other parts in a well known manner.

Conduit 11 is further provided with a telescoping section 16, preferably concealed above the lower edge of the piano case and extensible with the spool drawer as the latter is drawn forwardly. Thus the major, and if desired the whole, connection from the primary exhaust source 12 comprises a single conduit which, being of a relatively large size and substantial character, is not likely to get of order or deteriorate. While, as shown, this conduit is of metal and thus particularly durable, it will be understood that, because of its size, flexible rubber or composition tubing may be employed with good results.

It will thus be seen that by the present improvement, the parts of the pneumatic system of the instrument, which are controlled

by instrumentalities on or associated with the slideable drawer, are also mainly or wholly rigidly affixed to said drawer so that the connection between the controlling devices and the controlled devices is made by ducts not subject to extension, folding or other service movement, and that all of the controlled and controlling parts so associated with the adjustable drawer, may be connected to the main exhaust source by only one conduit. In order to permit mechanical playing of the piano, in different positions of the drawer and connected parts there is further provided, below the key bed and preferably carried thereby as shown, a series of relatively long rockers, which I will term couplers, or coupler wires, 17. These couplers are supported in racks 18 and 19. A single couple wire 17 appears in the detail view, Fig. 9, and is shown as provided with an offset crank portion 20. When in place this crank portion hangs down obliquely from its pivot ends 21 (see Fig. 5). Arranged to bear against the upper surface of the crank portions 20 of the coupler wires are a series of striker spindles 22, each provided at its bottom end with a felt covering 23, to rest silently against its respective coupler wire. At its upper end each spindle 22 has a felt covering 24, to rest silently against and under the rear end of its respective piano key 2, or other part of the piano action to which connection is desired. Likewise, below the series of coupler wires is arranged a series of striking spindles 25, each of which is connected at its lower end with a striker pneumatic 7 and is provided at its upper end with a felt covering 26, which is positioned to silently contact with the under surface of the crank portion 20 of its respective coupler wire. As shown in Figure 5, the crank portion of each coupler wire, when its pneumatic 7 is extended, hangs downwardly at an angle and rests between the buttons 26 and 23 of its pair of striking spindles 25 and 22, respectively. When an action pneumatic 7 is collapsed the crank portion 20 of its coupler is forced upwardly so as to transmit a striking blow to its spindle 22 (see Fig. 2), thence to the piano key 2, and thence to the hammer to effect the sound. The long crank portions 20 of the coupler wires are disposed horizontally and in the line of fore and aft movement of the drawer 3, so that whether the latter is drawn out to the position of Figure 4 or moved forwardly to concealed position, as shown in Figure 1, each action (or striker) pneumatic 7 is at all times operatively connected with its corresponding piano action. Consequently the instrument may be pneumatically operated when the drawer is in either extreme position, as well as in all intermediate positions.

The telescopic joint 16 in the main con-

duit 11 is preferably constructed as shown in Figures 7 and 8 and as there illustrated, the conduit 11 of metal has a straight horizontally and rearwardly extending portion 27 fitting through a short metal section 28. The section in turn, is glued or otherwise securely fastened at one end within a rubber pipe 29 of larger diameter and at the other end within a leather collar 30, also glued thereto. To insure a contracting fit, a coil spring 31 may be, if desired tensioned around the end of the collar 30 to press the same tightly against an inner collar or bushing 31^a and the tube end 27 to make an air tight joint. Tube 29, at its opposite end, is securely fixed to conduit 11' leading to the exhaust chamber 12. The telescopic joint thus described has been found permanently serviceable and air-tight. It is also economically manufactured and particularly efficient in service on account of its limited flexibility, due to the flexibility of the outer tubing 29, so that the assembly constitutes a telescopic joint, and, to a limited but sufficient extent, a universal joint.

The lyre of the instrument preferably comprises a pair of castings 32, right-angled in shape and secured at their upper and rear ends to the piano bed and carrying at their front and lower ends the usual foot-pedals and associated parts. The foot-pedals may conveniently operate through push rods 34 and 35 connected by rocker arms 36. The lower portion of the lyre may be in turn braced by an obliquely disposed rod 37.

In the preferred embodiment illustrated and hereinabove described, the pneumatic expression control mechanisms, as well as the action chest, striker pneumatics and associated parts are all mounted in or on the horizontally movable drawer. It will be understood, however, that the mounting of either of these parts on the drawer is contemplated, and gains to that extent the advantages resident in the improvement. By mounting the pneumatic action devices on the drawer, the major number of flexible and extensible tubes, as heretofore employed, is eliminated. By adding also the pneumatic expression mechanisms to the drawer, largely if not entirely eliminates the remainder of such small tubes, so that all use of small diameter rubber tubing in long lengths, and subject to folding or other service displacement occasioning wear and leakage, is avoided. At the same time, also, by the improved assembly of cooperating parts as disclosed, the complete pneumatic system of the piano may be manufactured and tested satisfactorily prior to its actual installation in the piano. Also, of course, a removal of the pneumatic system can be expeditiously effected at any time for inspection or repair. A further advantage,

of especial commerical importance, is the capability of the improved construction for application to and operation of the horizontal grand pianos of various makes and styles without alteration of piano case construction and design as heretofore commonly required.

It will be noted that my invention is susceptible of embodiment in structural forms other than that specifically illustrated in the accompanying drawings, all embraced within the broad aspects of the invention and intended scope of the following claims, and I therefore do not wish to be limited in any respect in so far as concerns the use of any particular expression mechanism, pneumatic action mechanism or music spool mechanism that may be installed in said drawer.

Having described my invention, what I claim is new and desire to secure by Letters Patent is:

1. In a grand player piano, in combination, a manual piano action, and a pneumatic player system co-operating therewith and including a drawer supported by the piano case and horizontally movable beneath the key bed and carrying in relatively fixed relationship therewith a tracker bar and striker pneumatics, with means of connection between said pneumatics and said piano action effective for playing in different positions of said drawer.

2. In a grand player piano, in combination, a drawer supported by the piano case and horizontally movable below the key bed and carrying in relatively fixed relationship a tracker bar, pneumatic action mechanism, with piano actions, and mechanical coupling means between said mechanism and actions whereby the same are maintained in operative playing relationship in different positions of said drawer.

3. In a grand player piano, in combination, a drawer supported by the piano case and horizontally slidable below the key bed and having affixed thereto and movable bodily therewith, a tracker bar and a pneumatic action, comprising striker pneumatics, a wind chest and tracker controlled valves between said wind chest and striker pneumatics, all of said parts being operable in different positions of said drawer.

4. In a grand piano, the combination with the piano having manually operable keys and actions to cooperate therewith, of a drawer supported by and slidable horizontally below the key bed and carrying in relatively fixed relationship thereto a tracker bar, action pneumatics and expression controlling mechanisms, with mechanical means for transmitting movement from the action pneumatics to the sounding devices of said piano, in different positions of said drawer.

5. In a grand piano, in combination, man-

ually operable piano actions including keys, a pneumatic player mechanism including a spool drawer adjustably supported by the piano below said keys and horizontally movable out and in to expose or conceal the music spools, striker pneumatics supported by and movable with said drawer, and mechanical means for transmitting movement from said pneumatics to complementary parts of the piano action in either the out or in position of said drawer.

6. In a grand piano, in combination, a manually operable action including keys, a pneumatic action including a spool drawer adjustably supported by said piano and below said keys and horizontally movable to expose or conceal the music spools, piano action actuating pneumatics supported by and movable with said drawer, and connections for transmitting movement from said pneumatics to complementary parts of the manual action in various positions of said drawer.

7. In a grand piano, in combination, a manually operable action including keys, a pneumatic action including a spool drawer adjustably supported by the piano and below said keys and movable horizontally to expose or conceal the music spools, actuating pneumatics supported by and movable with said drawer, and connections including an element on the drawer and a co-acting element in the piano case, said elements being relatively movable, and a coupler for transmitting movement from said pneumatics to parts of the manual action in both extreme adjustments of said drawer through the medium of said co-acting elements.

8. In a grand piano, in combination, a manually operable action including keys, a pneumatic action including a spool drawer adjustably supported by the piano below said keys and horizontally movable to expose or conceal the music spools, actuating pneumatics supported by and movable with said drawer, and connections including an element on the drawer and a co-acting element in the piano case, said elements being relatively movable, and a mechanical coupler for transmitting movement from said pneumatics to parts of the manual action in any adjusted position of said drawer through the medium of said coacting elements.

9. In a grand player piano, the combination with the piano, of a drawer slidably supported below the key bed, a horizontal guideway on said piano for said drawer, a unitary assembly of the controlled and controlling mechanisms of a pneumatic player system within said drawer and movable bodily therewith, and operable to play said

piano in various positions of adjustment of said drawer.

10. In a grand piano, the combination with the piano case, of a drawer supported by said piano below the key bed and horizontally slidable and having affixed thereto and carried thereby striker pneumatics, and wholly mechanical means carried partly by the piano case and partly by said drawer for transmitting power from said striker pneumatics to the piano keys in any adjusted position of said drawer.

11. In a grand piano, in combination, a key bed, a drawer slidably supported therebelow for horizontal movement and carrying in relatively fixed relationship a tracker bar and action pneumatics, means connecting the latter to the power source, and means for mechanically transmitting force from said pneumatic to the piano actions in various positions of said drawer.

12. In a grand piano, the combination of a drawer slidably supported by said piano below the key bed and a lyre including angle brackets connected with the key bed in the rear of said drawer and supporting damper operating pedals forwardly beneath said drawer.

13. In combination, a unitary drawer including a tracker-bar, action pneumatics and connecting ducts mounted in relatively fixed relationship, and means for slidably supporting said drawer on the underside of the key bed of a piano for independent horizontal movement to and fro, and means for mechanically transmitting movement from said action pneumatics to the actions of said piano in various positions of said drawer.

14. In a grand piano, in combination, a manual action, a pneumatic action slidably supported by the piano case for horizontal movement, and an operative connection between parts thereof, including a pair of spindles and an elongated crank member to receive motion from one and transmit motion to the other of said spindles in different positions of contact of said spindles with said crank.

15. In a piano, pneumatically actuated playing devices; all the component parts of which mechanism apart from the wind producing device, are contained in a drawer hung beneath the key-bed of said piano and means interposed between the piano action and the said drawer, whereby the pneumatic playing devices are in continual operative contact with the piano action in whatever position the drawer may be within the limits of the interposed means.

In testimony whereof I affix my signature.
FRANK C. WHITE.
